UNITED STATES PATENT OFFICE

LOUIS FLAXMAN, OF BALTIMORE, MARYLAND

DESIGN FOR A POCKETBOOK

Application filed August 1, 1929. Serial No. 32,262. Term of patent 3½ years.

To all whom it may concern:

Be it known that I, LOUIS FLAXMAN, a citizen of the United States, residing at Baltimore, State of Maryland, have invented a new, original, and ornamental Design for a Pocketbook, of which the following is a specification, reference being had to the accompanying drawing, forming part thereof.

I claim:

The ornamental design for a pocketbook, as shown.

In testimony whereof, I have hereunto subscribed my name this 14th day of November, 1929.

LOUIS FLAXMAN.
